**CASING PANEL CONSTRUCTION FOR
HEATING APPLIANCE**

Anthony M. Castello and Robert R. Cooper, Wichita,
Kans., assignors to The Coleman Company, Inc.,
Wichita, Kans., a corporation of Kansas

Filed Sept. 2, 1966, Ser. No. 576,887
4 Claims. (Cl. 126—90)

ABSTRACT OF THE DISCLOSURE

A space heating appliance for location within the room to be heated includes an exterior casing having at least one panel exposed to the room where the panel comprises in combination an outer panel member formed of thin sheet steel, an inner panel member formed of asbestos board, and a sheet of heat-reflective aluminum foil on the inner surface of the asbestos board. The outer surface of the asbestos board is adhesively attached to the inner surface of the steel sheet, and the aluminum foil is adhesively attached to the inner surface of the asbestos board. The steel sheet may range from .01 to .06 inch in thickness in combination with an asbestos board of thickness from $\frac{1}{32}$ to $\frac{3}{8}$ of an inch. The panel construction is particularly adapted for wall heaters to provide a combination of sound deadening and heat insulation.

The outer casings or cabinets for heating appliances such as wall heaters are ordinarily fabricated from light weight sheet metal such as sheet steel. Since the burner, combustion chamber, and heat exchanger operate in close proximity to the metal panels, the panels would become excessively heated if not insulated. The practice therefore has been to utilize conventional insulating material such as insulating matting formed from fiberglass, ceramic fibers, etc. While such expedients provide satisfactory insulation, they do not contribute any other desirable characteristics to the heater. In particular, it has been desired to provide wall heaters with sound dampening means. Not only is the sound of the operating burner and other internal noises, such as those caused by metal expansion or contraction, transmitted to the room through the casing walls, but the walls themselves can be a source of noise and discomfort. The light gauge metal forming the panels can be caused to vibrate and produce an unpleasant noise when it is accidentally struck or bumped with a solid object. While this may not occur with great frequency, it is still a problem which it has been desired to correct, and the noisy, "tinny" sound produced by striking the outside of the casing can be unpleasant and annoying to users of the heater.

It is therefore an object of the present invention to provide an improved panel construction for the exterior casing of a heating appliance which substantially overcomes the problems and difficulties described above. A related object is to provide an improved panel of the character described which not only overcomes the unpleasant sound and noise problems, but which also continues to provide satisfactory heat insulation. Still another object is to provide a panel construction of the character described which accomplishes the multiple functions of sound dampening and heat insulation without appreciably increasing the cost of the heater casing, and even in some embodiments achieving a decrease in cost. Further objects, advantages, and results will be indicated in the following specification.

Drawings

This invention is shown in an illustrative embodiment in the accompanying drawing, in which—

2

FIGURE 1 is a perspective view of a heater casing side panel embodying the features of the present invention;

FIG. 2 is a side elevational sectional view of the heater panel of FIG. 1;

FIG. 3 is a perspective view of a heater employing side panels like those of FIGS. 1 and 2;

FIG. 4 is an enlarged fragmentary sectional view as indicated at 4 on FIG. 2; and

FIG. 5 is an enlarged perspective view of a retaining clip which may be used with the panel construction.

Detailed description

Looking first at FIG. 3, there is shown a space heater W having side panels S. The heater shown is a free standing gas-fired vertical room heater. Interiorly, it includes a gas burner, a heater exchanger, a radiator, and a flue outlet. Since the construction of heaters of this general type is well known in the art, it will not be further discussed herein.

Turning now to a description of the panel construction of this invention, reference is made particularly to FIGS 1, 2, and 4. The casing panel S provides an outer panel member 10 formed of sheet metal. In the illustration given, metal sheet 10 provides the exterior of the side panel of the casing. It will be understood, however, that this invention may be applied to any or all panels of the heater cabinet, including either or both side panels, the bottom panel, the front panel and the top panel, or portions of the side, bottom, front, and top panels.

As indicated above, this invention is particularly adapted for use with casing panel members formed of relatively light weight or thin gauge sheet metal. While sheet steel is preferred, other sheet metals can be used such as aluminum. The invention is advantageous with metal sheets having thickness of from .01 to .06 inch, but usually the preferred thickness of the metal sheet will range from about .018 to .047 inch.

To provide an improved appearance or for convenience of assembly, the sheet metal casing member 10 can be formed integrally with right angle flange members, such as the side and top flanges 11 and 12. The inner ends of these side flanges may be provided with integral right angle flanges, such as the flanges 11a and 12a. It will be understood, however, that this invention is not limited to this particular means of fabricating a panel member.

In accordance with the present invention, the casing panel is provided with an inner panel member 13 which is formed of asbestos board. As shown more clearly in FIGS. 2 and 4, the asbestos board member 13 is arranged with its outer surface facing the inner surface of the sheet metal member 10. As indicated at 14 the facing surface of the asbestos board and the sheet metal member are adhesively united. This provides a firm bond between the asbestos board 13 and the sheet metal member 10.

The asbestos board 13 can be, either asbestos millboard or rollboard. For the purpose of the present invention these products are substantially identical in character, although the rollboard is somewhat more flexible than the millboard, and is sold in rolls rather than in flat sheet.

Both types of asbestos board are formed from asbestos fibers packed tightly together and united with a suitable fireproof adhesive such as sodium silicate. The asbestos board may contain a minor percentage of other fibrous material such as cellulose fiber. One commercial product which has been found particularly suitable is an asbestos millboard which can be described as a multi-laminar sheet consisting of approximately 90% asbestos combined with cornstarch and cellulose fiber, the sheet being produced on a cylinder paper machine, and sodium silicate being used as the laminating adhesive. Such millboard sheets have entirely different heat insulating properties than open fibrous mats of fiberglass, asbestos, or ceramic fibers. I

act, asbestos board, because of its density and continuous structure, has relatively poor heat insulating properties, and is not normally employed in applications where heat insulation is desired.

For the purpose of the present invention, the asbestos board preferably has a thickness of about $\frac{1}{16}$ to $\frac{1}{4}$ inch with a $\frac{1}{8}$ inch thick sheet being particularly suitable. However, the present invention can be advantageously employed with somewhat thicker or thinner asbestos board, such as asbestos board from about $\frac{1}{32}$ to $\frac{3}{8}$ inch thickness.

The adhesive employed for bonding the asbestos board to the sheet metal is not particularly critical. Many adhesives are suitable, including epoxy resin adhesives, rubber base adhesives, etc. For convenience of assembly, a temperature resistant contact cement can be used. Adhesives formed from synthetic rubber are particularly suitable. Commercial adhesives of this kind are sold by Minnesota Mining and Manufacturing Company. In general, any adhesives may be employed which are adapted or bonding fibrous material to metal, and which will not deteriorate under the ambient temperature conditions of a wall heater. The contact cement may be applied by brush application to the inner surface of the metal sheet 10 and to the outer surface of the asbestos board 13. The surfaces may then be brought together. Certain desirable high temperature type adhesives may be of the slow drying type. To assist in retaining the asbestos board against the heat metal wall during the drying process, suitable clip fasteners may be provided such as the lower clip 15 and the upper clip 16 as shown more clearly in FIG. 2. Clip 15 is provided with an attachment portion 15a which may be spot welded to the sheet metal wall 10, and with a bendable tab portion 15b which can be folded upwardly over the lower edge of the asbestos board 13 after the adhesive has been applied. The clip 16 is insertable at the top of the panel between flange 12a and the inner surface of the board 13. It includes spring tabs 16a and 16b which resiliently hold it in place. After the adhesive-coated asbestos board has been inserted, clip 16 may be snapped into place to hold the upper edge of the asbestos board against the sheet metal member 10.

To provide additional heat insulation, a sheet of heat reflective metal foil is applied to extend over the inner surface of the asbestos board member. In the illustration given, the metal foil sheet is designated by the number 7, as shown more clearly in FIG. 4. Preferably the heat insulating member 17 is formed from aluminum foil having its bright or polished surface outwardly. There is no particular advantage in a thick layer of metal foil, and therefore the thinner metal foils can be used, such as aluminum foils of .7 to 1 mil. More generally, aluminum or other reflective metal foils of from .5 to 3 mils can be used. Usually, however, the preferred thickness will be less than 2 mils. The heat reflective metal foil may be adhesively attached to the inner surface of the asbestos board 14 as indicated at 18 in FIG. 4. The adhesive may be of the same kind as used for joining the asbestos board to the metal wall.

The panel construction of the present invention provides the desired sheet metal vibration dampening improvement without sacrificing insulating properties. The heat insulation is comparable to that obtained by employing a foil-faced fiberglass insulating mat, which although equally or more expensive, provides little or no sound dampening properties. The panel construction of the present invention is simple, economical, and provides a com-

posite of desirable properties which have not heretofore been achieved in a sheet metal heater casing.

In the illustration given, the asbestos board 13 is shown extending for only about $\frac{2}{3}$ of the height of the sheet metal member 10. If desired, however, the asbestos board 13 may be extended completely to the bottom of the panel. For the particular wall heater shown in FIG. 3, it has not been found necessary to extend the asbestos board for the full length of the panel. The objects of the present invention are satisfactorily accomplished with the construction shown.

While in the foregoing specification this invention has been described in relation to a specific preferred embodiment thereof and many details have been set forth for purposes of illustration, it will be apparent to those skilled in the art that the invention is susceptible to other embodiments and that certain of the details described herein can be varied considerably without departing from the basic principle of the invention.

We claim:

1. In a space heating appliance for location within the room to be heated and including an exterior casing having at least one panel exposed to said room, the construction of said panel comprising in combination:

(a) an outer panel member formed of sheet steel having a thickness of .01 to .06 inch, said member comprising a portion of said exterior casing;

(b) an inner panel member formed of asbestos board having a thickness of from $\frac{1}{32}$ to $\frac{3}{8}$ inch,

said asbestos board member having its outer surface facing the inner surface of said sheet metal member and said facing surfaces being adhesively united; and

(c) a sheet of heat-reflective metal foil extending over and being adhesively attached to the inner surface of said asbestos board member.

2. The combination of claim 1 wherein said steel sheet has a thickness of from 0.18 to 0.47 inch.

3. The combination of claim 1 wherein said asbestos board has a thickness of from $\frac{1}{16}$ to $\frac{1}{4}$ inch.

4. In a wall heater including an exterior casing for mounting in the room to be heated, said casing having at least two side panels, each of said side panels comprising the combination of:

(a) an outer panel member formed of sheet steel having a thickness of from 0.18 to 0.47 inch, said member comprising a portion of said exterior casing;

(b) an inner panel member formed of asbestos board having a thickness of $\frac{1}{16}$ to $\frac{1}{4}$ inch,

said asbestos board member having its outer surface facing the inner surface of said sheet metal member and said facing surfaces being adhesively united; and

(c) a sheet of aluminum foil having a thickness of .5 to 3 mils extending over and being adhesively attached to the inner surface of said asbestos board member.
